UNITED STATES PATENT OFFICE.

ETHAN I. DODDS, OF PITTSBURGH, PENNSYLVANIA, ASSIGNOR TO FLANNERY BOLT
COMPANY, OF PITTSBURGH, PENNSYLVANIA.

STAY-BOLT STRUCTURE.

1,295,872.

Specification of Letters Patent.

Patented Mar. 4, 1919.

Application filed May 3, 1918. Serial No. 232,316.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as

5

sleeve 7 and lock the bearing sleeve 10 in place. The bearing sleeve 10 projects outwardly beyond the ring or sleeve 7 and may be made with an angular interior portion 13 to receive a wrench and a portion of the interior wall of said bearing sleeve 10 is threaded to receive a threaded plug 14 which serves to close the sleeve tightly over the 60

55

segmental shoulders 9 of the fixed ring or sleeve 7 and lock the bearing sleeve 10 in place. The bearing sleeve 10 projects outwardly beyond the ring or sleeve 7 and may be made with an angular interior portion 13 to receive a wrench and a portion of the interior wall of said bearing sleeve 10 is threaded to receive a threaded plug 14 which serves to close the sleeve tightly over the 69

AN extremely interesting and important result is that the segmental distribution of the α -helix in the β -barrel of the trypsin inhibitor is not random, but follows a definite pattern of alternating α -helices and β -sheets, which is typical of the β -barrel structure of globular proteins. The α -helices are located in the β -sheets, and the β -sheets are located in the α -helices. This pattern of alternating α -helices and β -sheets is a prominent feature of the trypsin inhibitor.
